[57] CLAIM

The ornamental design for a combined armored vehicle gun turret and control pit, as shown and described.

DESCRIPTION

FIG. 1 is a left-side elevational view of a combined armored vehicle gun turret and control pit illustrating my new design;

FIG. 2 is a top plan view thereof;

FIG. 3 is a right-side elevational view thereof;

FIG. 4 is a front elevational view thereof; and,

FIG. 5 is a rear elevational view thereof.
The broken lines in the drawing are for illustrative purposes only.

FIG. 1.

FIG. 2.

FIG. 5.

FIG. 4.
